UNITED STATES PATENT OFFICE

GLENN B. BANNISTER, OF HERMOSA BEACH, CALIFORNIA, ASSIGNOR TO METLOX CORPORATION, LTD., OF MANHATTAN BEACH, CALIFORNIA, A CORPORATION OF CALIFORNIA

DESIGN FOR A MARQUISE

Application filed November 1, 1930. Serial No. 37,489. Term of patent 14 years.

To all whom it may concern:

Be it known that I, GLENN B. BANNISTER, a citizen of the United States, and a resident of the city of Hermosa Beach, in the county of Los Angeles and State of California, have invented a new, original, and ornamental Design for a Marquise, of which the following is a specification, reference being had to the accompanying drawings, forming part thereof.

Fig. 2 is an enlarged detail perspective showing that portion of the marquise indicated between lines 2—2 of Fig. 1.

I claim:

The ornamental design for a marquise substantially as shown.

GLENN B. BANNISTER.
